UNITED STATES PATENT OFFICE.

JONATHAN L. KNIGHT, OF KANSAS CITY, MISSOURI, ASSIGNOR TO MILLARD F. BROWN, OF KANSAS CITY, MISSOURI.

COMBINATION-TOOL.

No. 874,409.

Specification of Letters Patent.

Patented Dec. 24, 1907.

Application filed July 9, 1907. Serial No. 382,904.

To all whom it may concern:

Be it known that I, JONATHAN L. KNIGHT, a citizen of the United States, residing at Kansas City, in the county of Jackson and State of Missouri, have invented certain new and useful Improvements in Combination-Tools, of which the following is a specification.

My invention pertains to improvements in combination tools, its object being to provide in a single instrument of convenient size, a number of hand operated small tools in general use.

The invention consists, primarily, in selecting such a list that any tool to be embodied in the combination, may have its parts so modified in form or details as to adapt it for connection and coöperation with the parts of the other individual tools of the group, without destroying its individuality, or detracting from its efficiency as a distinctive representative of its class. These conditions having been met, consideration has been given to the matter of harmonious and consistent association, or grouping together tools of the same general character, and those offering the widest field of general utility. The ultimate, and most important problems of the invention—the actual construction of its parts and details—has been to preserve the highest efficiency of each individual tool represented with the greatest possible degree of convenience and simplicity in its use. The forming, adjusting, arranging, and connecting the several parts in such a manner that the operations of any individual tool should not be handicapped by the presence in the group of any other, and that the aggregate collection—the combination tool—as a unit, or whole, should present a symmetrical, well proportioned, and pleasing appearance.

These several objects I attain by means of the mechanism illustrated in the drawing which accompanies and form part of this application, and in which:—

Figure 1 is an elevation of a combination tool constructed according to my invention. Fig. 2 is a plan view of the top, or upper edge 50 of the same.

Like reference letters and numerals designate like parts and details in both views—

principal parts and elementary details being indicated by letters, while minor details of construction are referred to by numerals.

55

Enumerating the ten different tools included in the combination, and describing the several parts of novel form which have been so devised that many of these have dual, and some multiform functions in the operative actions of the different tools, the crossed levers, A and B, will first be described, as they, by the novel details of form given them, in reality constitute almost the entire device—ten distinct tools—viz: 60 a hatchet—hammer—staple puller—cutting pliers—pipe tongs—wire cutter—tap wrench—tack or nail puller—screw-driver—and three size eyelet punch. This pair of crossed levers, A and B, for convenient distinction are referred to as lever handles. They are preferably composed of wrought or cast steel, but may be of any other suitable metal or alloy having necessary strength, and adapted to be tempered and receive cutting edges.

65

The lever A, at its short arm, in front of the fulcrum rivet, has the projecting hatchet blade, C, while the lever B, in like part of its length, has the hammer poll, D. The extreme front end of the lever A, is fashioned to form one jaw of a cutting pliers, E, while the corresponding part of the lever B, is fashioned in like manner to form the companion jaw, E'. The inner sides of the jaws E and E', are serrated with saw tooth notches to form gripping jaws of the pipe tongs, F and F'.

70

From the rear side of the hammer poll, D, is a cone shaped projecting lug or horn, H, 90 adapted by its form and position to be a convenient and effective staple puller. The upper rear or inner edge of the hatchet blade is serrated with saw tooth notches to form one wall of a V shaped tap or nut wrench, I, 95 while the clevis shaped fulcrum brace, J, has similar notches along its lower side to form the other wall, I'. By giving these two walls positions radial to each other, or sloping to form a wedge shaped space between them, the tap wrench becomes graduated to adapt it for gripping taps of different sizes, and of varying shapes from square to round. The clevis shaped piece, J, in addition to,

forming one wall or jaw of the tap wrench, also serves as a very secure brace to hold the handles in close contact without too tight riveting.

5 At a suitable distance from the fulcrum point of the levers to give desirable depth of mouth, or width of margin on the leather belt, or other article in which holes are to be punched, the handle or lever, A, has its vertical thickness increased by an upward projecting, semi-ovoid portion, 4, and through this enlarged portion extends a mortise, 5, in which is pivotally hung the three armed punch, K, each arm being a tubular punch, 15 no two of the same size. This graduated-size composite punch is secured in place by the cross rivet, 6, on which it may be turned to bring either of the three punching tubes to position for use. On the inner side of the 20 handle A, and in rear of the mortise, 5, is a hook shaped lug, 7, in which the clamping link, 8, is held when the tool is closed and its two handles clamped tightly in position while the tool is in use as a hatchet—hammer, 25 staple puller, or tap wrench. In vertical alinement with the punch, K, as it is located in the handle A, there is placed on the inner side of the handle B, a punch seat, L, on which the cutting end of the punch tubes 30 contact in the action of punching. This seat also has the additional function of forming the pivotal attachment for the clamping link, 8, the rivet or journal on which said link turns to mesh in the lug, when the levers 35 are to be clamped in position as a double handle of the hatchet, hammer, &c. This link is turned from under the lug when the tool is to be used as a plier, wire cutter, punch, &c. The rear end of the lever, A, is flattened 40 and fashioned to form a tack puller N, and the rear end of the lever, B, is in like manner flattened, to form a screw driver, M.

Having described the several parts and details of my invention, it is proper to explain 45 some of the more important reasons for giving them the novel forms, and disposing them in the special positions where they are seen. The pair of pivotally connected, crossed levers was adopted as the basic foundation, or fundamental feature of the device because that method of applying power in the manipulation of small hand operated tools, is most simple, convenient, and universally understood, alike by skilled mechanics 50 as well as novices. Moreover, crossed levers with oscillating movement round a pivotal center point of connection, offer a wide field for variation in details of form to adapt them as operative parts of a great variety of devices. In the combination tool here described, the long arms of the two levers, A and B, being brought to, and firmly clamped in position approximately parallel to each other, form a trussed, double, and very rigid 55 handle for the hatchet, hammer, &c.—a han-

dle which will neither become loose from use, pull out under stress, or break off at an inopportune time. The necessary enlargement of the short arms of the levers—their front ends, to afford material for the plier, pipe 70 tongs, and wire cutter jaws, gives desired additional weight, and consequently increases the impact of the stroke when the tool is used as hammer or hatchet. The tap wrench and staple puller, from their location, are 75 given great lever power, and by their form, or shape, have great strength to resist breaking. The jaws of the cutting pliers at the extreme ends of the short arms of the levers, differ from the jaws of ordinary cutting 80 pliers in having their concave inner surfaces serrated with the saw tooth notches to form the gripping jaws of a pipe tongs, a tool of infrequent use, but very convenient to have when needed. The wire cutter formed by 85 the elongated semi-circular depressions, has the special merits of operating by a shear cut movement, and from its location near the fulcrum point, is given enormous power of leverage, while the two blades of the shears 90 are held in close contact by the clevis brace through the ends of which the fulcrum rivet passes. The 3-fold, compound punch is arranged in T form, to the end that when the tool is to be used as a hammer, &c, with its 95 handles closed and clamped, the punch representing the vertical body of the T may rest on the seat, forming an additional brace in the trussed, double handle, while the other two punching tubes forming the cross head of the 100 T, rest in upper portion of the mortise, the projecting ovoid shaped enlargement protecting the hand from injury by the cutting ends of the punching tubes. When the tool is opened, and being used as a punch, if one 105 of the punches project beyond this enlargement of the handle its position would not endanger the hand, and if being used as a cutting pliers, wire cutter, &c, the punches can be turned to same position as when closed. 110 The screw-driver and tack puller, at outer ends of the long arms of the levers, derive no special advantage from their location, nor do they differ in form from similar tools in common use. They have been introduced to add 115 to the number of tools found available in the combination, and their location fixed by necessity, the position assigned them being the only place affording facilities for their convenient use.

Having thus described my invention, pointed out the reasons for, and the results of, its novel features and details of construction, what I claim as new, and desire to secure by Letters Patent of the United States, is:—

In a combination tool consisting essentially of a pair of crossed and pivotally connected levers, the clevis shaped fulcrum brace attached at the crossing portion of said 130

levers, the under side of said clevis brace being serrated with saw-tooth notches adapted to coöperate with a companion series of saw-tooth notches, said notched or serrated portions forming the two walls of graduated size

5 tap or nut wrench, substantially as shown and described.

Signed in presence of two witnesses this 6th day of July 1907.

JONATHAN L. KNIGHT.
